UNITED STATES PATENT OFFICE.

JAMES A. LANSING, OF SCRANTON, PENNSYLVANIA.

DOMESTIC RANGE.

1,124,640.

Specification of Letters Patent. Patented Dec. 22, 1914.

Application filed April 30, 1914. Serial No. 835,518.

To all whom it may concern:

Be it known that I, JAMES A. LANSING, a citizen of the United States, residing at Scranton, in the county of Lackawanna and State of Pennsylvania, have invented certain new and useful Improvements in Domestic Ranges; and I do hereby declare the following to be a full, clear, and exact description of the same, reference being had to the accompanying drawings, forming part of this specification, and to the figures and letters of reference marked thereon.

The object of the present invention is to provide a domestic range adapted primarily for cooking purposes with the use of gaseous fuel combined with a water heating arrangement adapted to be heated either by the consumption of gaseous fuel or solid fuel, to which ends the range embodies a water back, or coil through which water is circulated from an ordinary domestic boiler, one side of said water back being exposed to a combustion chamber adapted for the burning of solid fuel of any ordinary kind such as coal or wood and the other side exposed to a combustion chamber in which gaseous fuel is burned, there being an arrangement of dampers whereby the economical and safe operation of either the gaseous fuel burners or of the combustion chamber for solid fuel may be effected without being interfered with by the construction adapted for use in connection with the burner or combustion chamber which is for the time being not in use.

The invention further contemplates a domestic range in which the oven or portion of the range adapted for baking and the portion of the range adapted for cooking with ordinary exposed utensils may be utilized without being interfered with by the water heating and solid fuel burning portions of the range, all of said parts being embodied in a simple organized arrangement adapted for utilization by domestic help without particular mechanical knowledge or high mental ability.

Referring to the accompanying drawings.—Figure 1 is a sectional elevation through a domestic range embodying the present invention, certain of the parts being shown in outline, inasmuch as the detail construction of the same is not important. Fig. 2 is a section in a horizontal plane, showing the arrangement of the dampers for shutting off communication be-

tween the combustion chambers and flue. Fig. 3 is a section in a vertical plane through the oven at right angles to the plane of Fig. 1. Fig. 4 is a section in a horizontal plane showing a different arrangement of the dampers for controlling the escape of products of combustion from the several combustion chambers or burners. Fig. 5 is a perspective view of a range with parts broken away and in section, embodying the present invention but having separate ovens, one adapted to be heated by gas burners and the other by the combustion of solid fuel in a fire pot. Fig. 6 is a perspective view of a preferred form of damper.

Like letters of reference in the several figures indicate the same parts.

Referring particularly to Figs. 1, 2 and 3, the range adopted for illustrating the invention embodies a fire pot for solid fuel which is of more or less conventional form, and it is located in the range structure in the position where fire pots are most generally located in ranges of this type. At one side of the fire pot there is an oven, and on the opposite side of the fire pot there is a water front, commonly called a water back, beyond and below which is the combustion chamber for gaseous fuel for heating the water back, although, as will be presently apparent, this particular order of arrangement is not essential, for the oven and water back may be located on the same side of the fire pot. In every instance, however, provision is made whereby the products of combustion may be led off from the oven or from the fire pot or from the water heating combustion chamber into a flue box, and suitable dampers are provided whereby the chambers may be shut off from communication with the flue so as to prevent interference with the operation of the other burners or fire pot. In said Figs. 1, 2 and 3, the oven portion of the range is indicated generally by the letter A and adapted to be heated by gas burners A', and it may embody a broiler burner A'' located near the top of the oven, as shown. Above the oven there is a space B in which the usual top burners are located. These burners are indicated at C and they may be beneath a solid or griddle top, or beneath a grating top D of the ordinary type. The flue F for carrying off products of combustion from the oven burners is located between the top of

the oven and pan or floor below burner C. It has an opening F, and the space above the oven in which the burners C are located has an opening F'. Both of said openings 5 lead into a flue box G located at the back of the range and through which communication is had with a stove pipe or smoke stack connection H. The flue box G extends along the back of the range, and the fire pot I 10 communicates therewith through an opening i, best seen in elevation in Fig. 1. On the oven side the fire box may have the usual fire brick lining k and the fuel is supported by a grate such as the Dockash grate K 15 illustrated. On the opposite side of the fire box from the fire brick lining k, said box is defined by a water back L through which water is circulated from an ordinary domestic boiler shown in dotted lines at S 20 through pipe connections indicated at l in Fig. 3. On the side of the water back away from the fire box a combustion chamber for gaseous fuel is formed, which combustion chamber is entirely independent of the fire 25 box and its ash pit, so that dust will not be liable to find its way into the same. This combustion chamber is preferably defined by the removable end wall M' of the range in Fig. 1, which conveniently is the inner 30 wall of a door M having slide damper controlled openings m therein preferably at top and bottom, through which air is admitted to the lower part of the combustion chamber a considerable distance below the 35 water back. The door fits an opening in the permanent end wall M² of the range structure. The chamber on the gas burner side of the water back communicates with the flue box at the rear of the stove through an 40 opening N, and between the several openings in the flue box the box is provided with dampers whereby the passage of products through it may be arrested at will. As shown in the drawings, dampers O and O' 45 are pivotally mounted at their lower edges in the flue box so as to turn up into position for closing the box or down into position for permitting the free passage of products therethrough, and for operating said 50 dampers, the usual damper rods o, o' extend out to the front of the range, where they are readily accessible and the dampers may be opened or closed at will depending upon which of the combustion chambers is to be 55 utilized for generating heat. Various arrangements of the flue box and dampers will at once occur to those familiar with the art of range construction, and in Fig. 4 an arrangement is illustrated in which, instead 60 of the damper O in the flue box for closing communication with the gas burner side of the water heater, a long pivoted damper is provided at O² which controls a correspondingly shaped opening between the fire box 65 and chamber, whereby the products of com- busion from the gas burner side of the fire box may be permitted to pass into the top of the fire box and thence into the flue box, or when the fire box is used exclusively, said damper may be closed and the admission of 70 air above the fuel prevented. A long damper, such as O², may be combined with the flue box damper O, and this is the preferred arrangement, as shown in Figs. 1 and 75 6, where the long damper is indicated by the reference letter O³. The arrangement is such that when one is open the other is closed, and vice versa. When the long damper O³ is opened the heated products of combustion from the gas burner chamber 80 are sent through the upper portion of the fire box to the flue box and stack connections, and this arrangement is desirable inasmuch as it permits of the utilization of 85 such heated products for the purpose of drying out or incinerating garbage, etc., which may be placed in the fire box in a suitable receptacle, without the necessity of building a fire in the fire box. 90

In a range embodying a water heater adapted to be heated by either solid or gaseous fuel combustion, great difficulty has been experienced in devising an arrangement which would heat the water by the combustion of gaseous fuel in a reasonable 95 time, and to a sufficient degree, which fact probably accounts for the failure of devices of this character to be more generally used. After a long series of experiments I have ascertained that with an arrangement such 100 as illustrated wherein a series of superposed gas burners are employed located mainly below the bottom level of the water heater and the flue so arranged that adequate oxygen is supplied to the several superposed 105 burners, and a large volume of heated air caused to sweep over the water heater, the heating operation by use of gaseous fuel may be successfully and economically accomplished. By reference to the drawings 110 it will be seen that three long gas burners R, R' and R² are arranged in the chamber, two of said burners being located below the bottom level of the water back and the other 115 of said burners being located opposite the lower portion of the outer face of said water back. From the latter burner the flame impinges directly against the surface of the water back and from the lower burners the flame is directed toward that side of the 120 chamber on which the water back is located, so that the effect of the heat and flame is to heat the water back on the side and bottom as well as the metal immediately adjacent and in conductive relation thereto. With this arrangement the burners receive an adequate supply of oxygen, and one does not interfere with the operation of the other. The burners are preferably independently controlled as are all 125 130

beginning of the second, the machine is programmed to have the wheel in the beginning position and then rotates it clockwise with the same speed until a comparatively small volume of 0.04 liter is reached. The volume of 0.04 liter is reached in one or two minutes.

the box and gas burner chamber, respectively, dampers for controlling the flow of products from the chamber and oven flues through the fire box, and a stack connection with said fire box to which the products are fed.

3. In a domestic range, the combustion will, as usual, a fire box for the consumption of solid fuel, a water back at one side of said fire box, and a gas burner chamber 75 on the side of said water back away from the fire box, of a fire box at the rear of the range for carrying off the products from the oven, burner and gas burner chamber, and a gas water damper for arresting the 80 flow of products from the oven and gas burner chamber, respectively, whereby the combustion of solid fuel in said fire box will not be interfered with.

85 In a domestic range, the combination
86 will comprise a fire box for the combustion
87 of solid fuel having an ash box below the
88 same, a water back at one side of said fire
89 box, and a gas burner chamber on the side
90 of said water back opposite the fire box and
91 having air admission openers independent
92 of the fire box and its ash box, a flue box
93 at the rear of the range having a stack con-
94 nection for carrying off the products of
95 combustion from the gas burner chamber,
96 fire box and oven, respectively, and inde-
97 pendent dampers controlling the passage of
98 products of combustion from the oven and
99 gas burner chamber through the flue box
100 whereby the combustion of fuel in the fire
101 box will not be interfered with by the ad-
102 mission of air between the fire box and
103 said gas burner.

being so arranged with relation to each other, that when one is opened the other is closed, and vice versa.

6. In a domestic range, the combination 5 with an oven, a fire box for the consumption of solid fuel, a water back at one side of said fire box and a gas burner chamber on the side of said water back away from the fire box and in immediate proximity 10 thereto, of a flue box at the rear of the range for carrying off the products from the oven, fire box and gas burner chamber, and a pivoted damper having wings arranged at an

angle with relation to each other, one wing controlling the communication between the gas burner chamber and flue box and the other controlling the communication between the gas burner chamber and fire box, the arrangement of the wings being such that when one is in closed position the other 15 20 is in open position, and vice versa.
